UNITED STATES PATENT OFFICE.

JOHN N. KITCHEN, OF WHITE POST, VIRGINIA.

CAR-COUPLING.

SPECIFICATION forming part of Letters Patent No. 539,687, dated May 21, 1895.

Application filed March 25, 1895. Serial No. 543,131. (No model.)

To all whom it may concern:

Be it known that I, JOHN NEWTON KITCHEN, a citizen of the United States, residing at White Post, in the county of Clarke and State 5 of Virginia, have invented a new and useful Improvement in Car-Couplings, of which the following is a specification.

The object of my improvement is to provide such construction for coupling cars of the ar- 10 row-head and jaw type, as will cause the separation of the cars from each other, in the event of being derailed and overturned; and to ren- der the coupling safe, strong and secure.

The accompanying drawings illustrate 15 my improved coupling for railroad cars, in which—

Figure 1 shows in vertical section a portion 20 of two cars in coupled relation. Fig. 2 is a horizontal section of the same, taken through the coupling parts. Fig. 3 shows the coupling-bar, and Fig. 4 shows in front view the jaws in the platform-opening.

The end of each car is suitably constructed 25 to receive a pair of jaws 1, 1, which are considerably wider than they are thick and stand edge-wise across and at the end of the car. They are fitted in strong guides 2 in the platform and are pressed toward each other by springs 3 so that they are free to move toward 30 and be forced from each other, their inward movement being limited by suitable stops 4, so that their inner ends stand apart sufficiently to receive the coupling-bar and are rounded for this purpose so as to form curved 35 faces 5 on each side of the opening 6, into which the arrow-head of the coupling-bar enters, in coupling the cars. At their inner sides these jaws form abutments 7 to receive the shoulders of the arrow-head of the cou- 40 pling-bar. Each car is thus provided at each end with spring sustained jaws arranged to form a vertical opening three times or more in height greater than its width, and forming be- 45 tween them a space having a width slightly less than that of the coupling-bar. The curved faces of the jaws flare into the larger opening 6 in the end of the platform between the parts which cover and support the jaws.

The coupling-bar is formed with an arrow- 50 head 8 at one end and a wide flat narrow head 9 at its other end, the part between these heads being round at its junction with the

arrow head. The flat head stands at right angles to the position of the arrow-head and has a hole 10 passing through its greatest width and therefore at right angles to the arrow-head. The diameter of the round part and the thickness of the arrow-head and the wide flat head, are the same or substantially the same, and the bar has a length sufficient 55 to couple the cars and give freedom for turning. At each end of the car the platform has a vertical hole 11, passing through it longitudinally central with the opening between the jaws and in rear thereof to receive a coupling 60 pin 12, which may be connected by a chain or otherwise for use at each end of the car. The coupling-bar is secured by the coupling-pin so that the wide flat head is pivoted in edge- 65 wise position and stands vertically between 70 and is pressed on each side by the jaws, ren- dering it impossible for the bar to turn or be turned because of the position of its flat head between the jaws and the passing of the coup- 75 ling-pin edgewise through the flat head. This 80 is the important matter of my invention and it will be seen that while the coupling-bar cannot turn when the cars are coupled, the coupling-pin as a pivot, permits the bar to have a pivotal movement sidewise between 85 the jaws, for the proper movement of the coupling-bar to allow the cars to turn curves, the jaws yielding for this purpose. This safe holding of the coupling-bar at its wide flat head to prevent it from turning, holds the 90 arrow-head in certain engagement with the jaws of the coupled car. This maintaining the shoulders 13, 13 of the arrow-head in se- 95 cure and safe engagement with the inner sides of the jaws, permits the automatic uncoupling of the arrow-head and its withdrawal from the jaws, in the event of the overturning of either or both of the coupled cars. This uncoupling takes place as soon as one car turns over at a sufficient angle on its side to 100 release the engagement of the shoulders of the arrow-head from the jaws, as said shoul- ders approach in alignment with the opening between the jaws and free of them. The turning over of one car quicker than the con- nected car will tend to release the arrow- head, and the irregular turning of the con- nected cars will tend to the same result. In any case of the turning over of the cars, the

engagement is made very uncertain and in this particular becomes a matter of the last importance in preventing the loss of life and the destruction of the cars.

5 The coupling-pin engages the flat end of the coupling bar with one car and the arrow-head of the coupling-bar engages the jaws of the connected car.

I make the hole in the flat-head slightly oval to facilitate the coupling of the bar with the pin, which, passing through coincident holes in the upper and undersides of the platform of the car, passes also through the hole in the flat-head of the coupling-bar, in such 15 relation to the jaws as to maintain the coupling-bar in proper position for coupling its arrow-head with the jaws of the next car. The coupling-pin engaging in the hole in the wide-flat head edgewise and the said head 20 fitting the top and the bottom of the opening serves to hold the coupling-bar from sagging.

By making the bar of round cross section at its junction with the arrow-head permits it to turn between the jaws with the turning 25 over of the car.

It will be understood that the flat-head of the coupling-bar can be secured by the coupling pin in either end of the car and that the arrow-head can be coupled with the jaws in 30 either end of the car.

As the flat-head of the coupling-bar stands

vertical with its top and bottom edges against the top and bottom walls of the opening, and as the coupling-pin passes vertically and edge-wise through the flat head, the bar will be 35 kept in a horizontal and true position at all times and is thereby rendered certain to couple with the next car.

I claim as my improvement—

1. In a car coupling, the combination of the 40 spring sustained jaws arranged crosswise at each end of the car, with a coupling-bar having an arrow-head at one end, a wide flat head at its other end standing at right angles to the arrow-head and of round cross section between 45 said heads and a pin for engaging a hole extending through said flat head at right angles to the arrow-head, and through corresponding holes in the upper and under sides of the platform of the car, substantially as described. 50

2. For use in coupling cars provided with spring sustained jaws and coupling pins, an arrow-head coupling-bar having at one end a wide flat head at right angles to the arrow-head, and formed with a hole extending 55 through it in the direction of its greatest width as shown and described.

JOHN N. KITCHEN.
